PRESSURE FLUID MOTOR

John C. Curtis and Charles F. Osgood, Claremont,
N. H., assignors to Sullivan Machinery Company,
a corporation of Massachusetts

Application November 1, 1940, Serial No. 363,925

15 Claims. (Cl. 121—19)

This invention relates to pressure fluid motors, and more particularly to improvements in the fluid distributing valve mechanism of a pressure fluid motor of the reciprocating piston type.

An object of the present invention is to provide an improved pressure fluid motor. Another object is to provide an improved fluid distributing valve mechanism for a pressure fluid motor. Yet another object is to provide an improved valve mechanism of the double valve type. A still further object is to provide an improved double valve mechanism wherein the fluid distributing valves are separated by an intermediate sleeve which improves the sealing of the valves to prevent fluid leakage. Another object is to provide an improved double valve mechanism wherein identical fluid distributing valves are employed, the valves having like operating functions and being interchangeable without affecting their operating functions. A still further object is to provide an improved double valve mechanism wherein machining and finishing of the valves are simplified while sealing to prevent leakage of fluid past the valves is improved. Still another object is to provide an improved sleeve interposed between a pair of relatively movable fluid distributing valves wherein sealing of the valves is improved, the sleeve also serving as a valve actuating and holding element engageable with the valves whereby when one valve moves toward open position it imparts through the sleeve a force for shifting the other valve toward and holding the same in its closed position. These and other objects and advantages of the invention will, however, herein-after more fully appear.

In the accompanying drawing there is shown for purposes of illustration one form which the invention may assume in practice.

In this drawing:

Fig. 1 is a view in longitudinal vertical section through a pressure fluid motor embodying a valve mechanism constructed in accordance with an illustrative embodiment of the invention.

Figs. 2 and 3 are views similar to Fig. 1, showing parts in different positions.

Fig. 4 is an enlarged fragmentary sectional view taken on the plane of Fig. 1, illustrating the improved valve mechanism.

Fig. 5 is a perspective view of the intermediate sleeve.

In this illustrative embodiment of the invention 1 generally designates a pressure fluid motor which may be of the same general type as that disclosed in a copending application of J. C. 55

Curtis, Serial No. 315,786, filed January 26, 1940, now matured into Patent No. 2,224,861, granted Dec. 17, 1940.

The pressure fluid motor disclosed herein comprises a motor cylinder 2 having a bore 3 containing a reciprocatory motor piston 4. The motor cylinder has a rear head 5 and a front head 6, and the motor piston has a piston head 7 slidably fitting the cylinder bore and a forwardly projecting cylindric portion 8 guided in the bore of a sleeve 9 suitably secured within the front motor head. Also formed in the motor cylinder and arranged in axial alignment with the cylinder bore at the rear end of the latter is an enlarged bore 10, and the rear cylinder head has a cylindric portion fitted within the bore 10 in the manner shown in Fig. 1. Also arranged in the bore 10 is a cylindric valve box 11 having a cylindric valve box cover 12 abutting its rear face. An annular member 13 is also arranged in the bore 10 intermediate the valve box cover 12 and an annular member 14. A rear head block 15 abuts the rear face of the member 14 for clamping the parts 5, 11, 12 and 13 in position within the bore 10, and a suitable dowel pin is provided for holding the parts in proper relation. The valve box 11 has aligned, end, valve-receiving bores 16 and 17 connected by a reduced bore 18 in an intermediate partition 19. The rear head 5 has a rearwardly projecting, cylindric, sleeve-like extension 20 fitting tightly within a bore 21 in the valve box cover 12. The walls of the bores 16 and 17 and the exterior surface of the extension 20 cooperate to provide the inner and outer concentric walls of a pair of valve chambers 22 and 23, and the opposite surfaces of the partition 19 and the inwardly facing surfaces of the cylinder head 5 and the valve box cover 12 provide the inner and outer end walls of the valve chambers. Arranged in the valve chambers is a pair of relatively movable, fluid actuated, fluid distributing valves 24 and 25 respectively controlling the flow of pressure fluid to the opposite ends of the cylinder bore. Interposed between the valves is a cylindric sleeve 26 slidably fitting at its exterior periphery the bore 18 in the partition 19. The valves 24 and 25 are identical in design and shape and have like operating functions so that they may be interchanged without affecting their operating functions. The valves have sleeve-like bodies 27 and 28 slidably telescoped fitting the bore of the sleeve 26, and projecting outwardly from the valve bodies are annular flanges 29 and 30 respectively, these valve flanges slid-

ingly fitting the valve box bores 16 and 17. Projecting inwardly of the valve bodies are internal annular flanges 31 and 32 which respectively cooperate with an external cylindric portion 33 integral with the valve box cover and an external cylindric portion 34 integral with the rear cylinder head as shortly explained. Within the valves and intermediate sleeve is an internal fluid supply chamber 35, and the internal valve flanges 31 and 32 and the cylindric portions 33 and 34 cooperate to provide relatively restricted or metered flow of pressure fluid from the internal supply chamber 35 past the valves to the opposite ends of the motor cylinder bore. The remote end faces of the sleeve-like valve bodies 27 and 28 provide annular end-seating surfaces 36 and 37 respectively, the former being adapted to seat against the front face of the valve box cover and the latter against the rear face of the rear cylinder head. Formed on the front face of the valve box cover 12 and communicating with the rear valve chamber 22 is an annular recess 38 connected by a port 39 with a fluid distributing passage 40, the latter in turn being connected by a port 41 with the front end of the cylinder bore. Fluid distributing passages 42 in the rear cylinder head 5 connect the front valve chamber 23 directly with the rear end of the cylinder bore.

The means for supplying pressure fluid to the fluid supply chamber 35 within the valves and intermediate sleeve comprises a throttle valve 45 arranged in a transverse bore in the rear head block 15 and having an internal fluid supply chamber 46 connectible by a port 47 in the valve with a passage 48 in turn communicating with a chamber 49 in the member 14. Pressure fluid may be conducted from the chamber 49 through passages 50 and the bore of the member 13 to passages 51 in the valve box cover. Passages 51 communicate with an annular recess 52 in turn connected to an annular passage 53 surrounding the rear head extension 20 and formed within the cylindric portion 33. The passage 53 communicates directly with the fluid supply chamber 35 within the valves and intermediate sleeve. The valve chambers at the inner adjacent sides of the external valve flanges 29 and 30 are connected to the cylinder bore through throwing passages 54 and 55 respectively, which are respectively connected to the valve box bores through ports 56 and 57 and to the cylinder bore through ports 58 and 59. Formed in the walls of the cylinder bore substantially midway between its ends is an annular exhaust groove 60 connected directly to atmosphere through an exhaust port 61. The ports 58 and 59 of the valve-throwing passages communicate with the cylinder bore at points spaced longitudinally of the cylinder bore at the opposite sides of the exhaust groove 60 in the manner shown. Pressure fluid may flow from the internal fluid supply chamber 35 past restricted clearance spaces 62 and 63 at the inner peripheral edges of the internal valve flanges 31 and 32 respectively so that the flow of pressure fluid past the valves to the fluid distributing passages 40 and 42 is always maintained constant irrespective of any wear of the valves, the valves being guided solely at their exterior peripheries. The intermediate sleeve 26 slidily fitting the bore 18 of the partition 19 and the exterior surfaces of the sleeve-like valve bodies 27 and 28 provides a fluid-tight seal to prevent fluid leakage past the valves while enabling location of the valves in close adjacency. By making the valves identical, the

same may be readily assembled and machining and finishing are simplified, and also the valves may be interchanged at will without affecting their operating functions. The valves 24 and 25 and intermediate sleeve 26 divide the valve chambers into inner and outer spaces, and the fluid supply communicates with the inner space while the valve throwing means has communication with the outer spaces. It will be evident, however, that the parts may be reversed if desired so that there is an external fluid supply and internal valve-throwing connections.

The mode of operation of the improved pressure fluid motor will be clearly apparent from the description given. When the parts are in the position shown in Fig. 1, pressure fluid may flow from the supply chamber 35 within the valves and intermediate sleeve 26, through the restricted clearance space 63, through the valve chamber 23 past the front face of the front valve 25 and through the fluid distributing passages 42 to the rear end of the cylinder bore at the rear side of the motor piston, the pressure fluid acting on the rear pressure area of the piston head to move the piston forwardly to effect its working stroke. Concurrently, the front end of the cylinder bore at the front end of the piston head is connected to exhaust through the exhaust groove 60 and exhaust passage 61. The front valve 25 is at this time held in its rearward position by the pressure fluid acting on the effective front pressure area of the valve, and the latter, due to its abutting engagement with the sleeve 26, acts, through the intermediate sleeve, to hold the rear valve 24 in its closed position against the front face of the valve box cover. As the motor piston moves forwardly from the position shown in Fig. 1, the leading edge of the piston head first overruns the port 59 of the throwing passage 55, and thereafter the leading edge of the piston head overruns the exhaust groove 60, thereby cutting off communication of the front end of the cylinder bore with exhaust; and upon continued forward piston movement the leading edge of the piston head overruns the port 58 of the throwing passage 54. Thereafter the following edge of the piston head uncovers the port 59 of the throwing passage 55, admitting pressure fluid from the rear end of the cylinder bore through the throwing passage and port 57 to the valve box bore 17 at the rear side of the external valve flange 30 of the front valve 25. Due to the restriction at 63 between the internal pressure chamber 35 and the valve box bore 17 at the front side of the front valve 25 and the relatively free flow of fluid from the front end of the valve box bore 17 to the rear end of the cylinder bore through the passages 42, the pressure of the fluid at the rear side of the internal valve flange 32 is substantially greater than the pressure in the valve box bore at the front side of the valve, so that when throwing pressure is admitted to the throwing passage 55 the effective pressure acting on the external valve flange 30 is sufficient to throw the front valve forwardly from the position shown in Fig. 1 to the position shown in Fig. 2. When the front valve 25 moves to its foremost position shown in Fig. 2, the annular end-seating surface 37 thereon seats against the rear face of the rear cylinder head 5, but the rear valve 24 remains momentarily seated against the front face of the valve box cover. The rear valve is maintained in its rearmost closed position by the pressure of the fluid acting on the then exposed forward

end pressure area of the sleeve 26 which abuts the rear valve. When the valves are both held closed, as shown in Fig. 2, flow of pressure fluid to both ends of the cylinder bore is momentarily concurrently completely cut off and forward movement of the piston continues under the expansive action of the pressure fluid within the rear end of the bore and momentum. The pressure fluid trapped within the front end of the cylinder bore is compressed by the piston, and, when the following edge of the piston head uncovers the exhaust groove 60, the pressure areas at the opposite sides of the external flange of the front valve and the pressure area at the front end of the intermediate sleeve 26 are connected to atmosphere. The compression pressure built up by the motor piston within the front end of the cylinder bore transmitted through port 41, passage 40 and port 39 to the effective rear pressure area of the external flange of the rear valve 24 then acts to throw immediately the latter from the position shown in Fig. 2 to its position shown in Fig. 3. It will be evident, however, that if the pressure in the rear end of the cylinder, in passage 55 etc., drops low enough, due to expansion, before the exhaust groove is uncovered (as may easily be caused to take place by appropriate design) valve throwing concurrent with or slightly prior to rear end release, can be secured. When the valves 24 and 25 are in the position shown in Fig. 3, pressure fluid may flow from the supply chamber 35 within the valves and intermediate sleeve through the restricted clearance space 62, through the valve box bore 16, past the rear face of the rear valve 24 and through recess 38, port 39, passage 40 and port 41 to the front end of the cylinder bore at the front side of the piston head, the pressure fluid acting on the forward pressure area of the piston head to move the piston rearwardly to effect its return stroke. Concurrently, the rear end of the cylinder bore at the rear side of the piston head is connected to exhaust through the exhaust groove 60 and exhaust passage 61. The rear valve 24 is at that time held in its forward position by the pressure fluid acting on the rear pressure area of the valve, and the latter, due to its abutting engagement with the sleeve 26, acts, through the sleeve, to maintain the front valve in its closed position against the rear face of the rear cylinder head 5. As the motor piston moves rearwardly from the position shown in Fig. 3, the leading edge of the piston head first overruns the exhaust groove 60, thereby cutting off communication of the rear end of the cylinder bore with exhaust; and upon continued rearward piston movement the leading edge of the piston head overruns the port 59 of the throwing passage 55, and thereafter the following edge of the piston head uncovers the port 58 of the throwing passage 54, admitting pressure from the front end of the cylinder bore through the throwing passage 54 and port 56 to the valve box bore 16 at the forward side of the external flange 29 of the rear valve 24. Due to the restriction at 62 between the internal pressure chamber 35 and the valve box bore 16 at the rear side of the rear valve and the relatively free flow of fluid from the rear end of the valve box bore to the front end of the cylinder bore through the passage 40, the pressure of the fluid at the forward side of the internal valve flange 31 is substantially greater than that in the valve box bore at the rear side of the rear valve, so that when throwing pressure is admitted to the valve box bore 16

at the front side of the external valve flange 29 the effective pressure is sufficient to throw the rear valve rearwardly from the position shown in Fig. 3 to the initial position shown in Fig. 1. When the rear valve 24 is in its rearmost position shown in Fig. 1, the annular end-seating surface 36 thereon is seated against the front face of the valve box cover while the front valve 25 is maintained seated against the rear face of the rear cylinder head by the pressure of the fluid acting on the then exposed rear pressure area of the sleeve 26 which abuttingly engages the front valve. The front valve 25 will be opened by compression pressure acting through the passages 42 at least by the time piston head 7 in its rearward movement uncovers the exhaust groove 60, at which time, as will be evident, the valve-holding force provided by the action of pressure fluid transmitted from the front end of the cylinder bore upon the rear end of the sleeve 26 will be relieved. When the front valve 25 is opened, it returns to the position shown in Figs. 1 and 4, and acts to hold the rear valve 24 closed by pressure transmitted through the sleeve 26. The sequence of events above described is rapidly repeated during normal operation of the motor.

As a result of this invention it will be noted that an improved pressure fluid motor is provided having improved fluid distribution means whereby pressure fluid is distributed to the motor cylinder in an improved and more effective manner. It will further be evident that by the provision of an improved valve mechanism of the double valve type having an intermediate sleeve engaging both valves, not only is sealing of the valves to prevent fluid leakage improved, but also machining and finishing of the parts are simplified. It will further be noted that by the provision of a double valve mechanism wherein identical valves having like operating functions are employed, the valves may be interchanged without affecting their operating functions. Other uses and advantages of the improved pressure fluid motor will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In combination, in a motor, a cylinder, a piston reciprocable in said cylinder, and fluid distribution means for the motor including means providing a valve chest, fluid distributing passages leading from said valve chest to the opposite ends of said cylinder, a pair of fluid distributing valves arranged within said valve chest and an intermediate sleevelike member separating said valves and adapted to abut the latter in certain positions thereof, said valves being movable relative to each other and said sleevelike member, and said valves and sleevelike member being movable relative to the valve chest, said valves and sleevelike member cooperating with the valve chest in one position of said valves to provide internally of said valves and sleevelike member a chamber sealed from communication with said cylinder through said passages, and means for delivering motive fluid to said internal chamber for distribution there-

from under the control of said valves through said passages to the opposite ends of said cylinder.

2. In combination, in a motor, a cylinder, a piston reciprocable in said cylinder, and fluid distribution means for the motor including means providing a valve chest, fluid distributing passages leading from said valve chest to the opposite ends of said cylinder, a pair of fluid distributing valves arranged in said valve chest and an intermediate sleevelike member separating said valves and with which the latter are adapted to abut in certain positions thereof, said valves movable relative to each other and said sleevelike member, and said valves and sleevelike member movable relative to said valve chest, an internal fluid supply chamber provided within said valves and sleevelike member, said valves controlling the flow of pressure fluid from said internal fluid supply chamber to said passages, and means for effecting throwing of said valves including pressure areas on each of said valves to which fluid is delivered to effect valve closure and means under the control of said piston for delivering fluid to and venting fluid from said pressure areas.

3. A pressure fluid motor comprising, in combination, a cylinder, a piston therein, and fluid distribution means for the motor including passage means for supplying operating fluid to the opposite ends of said cylinder at the opposite sides of said piston respectively, an operating fluid supply, fluid distributing valve means including a pair of relatively movable valves and an intermediate sleevelike member separating said valves, said valves abuttingly engageable with said sleevelike member in positions wherein one valve exerts a pressure on said sleevelike member to hold the other valve stationary, and said valves respectively controlling the flow of operating fluid to the opposite ends of said cylinder by controlling the communication of said passage means with said fluid supply, and valve-throwing means for subjecting said valves to valve-throwing pressures to move said valves into their different operating positions, said valves in certain positions thereof momentarily completely cutting off communication of both of said passage means with said fluid supply.

4. A pressure fluid motor comprising, in combination, a cylinder, a piston therein, and fluid distribution means for the motor including passage means for supplying operating fluid to the opposite ends of the cylinder at the opposite sides of the piston respectively, an operating fluid supply, fluid distributing valve means including a pair of relatively movable valves and an intermediate sleevelike member separating said valves, said valves movable into abutting engagement with said sleevelike member and respectively controlling the flow of operating fluid to the opposite ends of said cylinder by controlling the communication of said passage means with said fluid supply, and valve-throwing means for subjecting said valves to valve-throwing pressures to move said valves into their different operating positions, one of said valves being held in closed position by the other valve abuttingly acting on said sleevelike member, and said valves in certain positions when one of them is out of abutting engagement with said sleevelike member momentarily concurrently completely cutting off communication of both of said passage means with said fluid supply.

5. A pressure fluid motor comprising, in combination, a cylinder, a piston therein, and fluid distribution means for the motor including passage means for supplying operating fluid to the opposite ends of said cylinder at the opposite sides of said piston respectively, an operating fluid supply, fluid distributing valve means including a pair of relatively movable valves and an intermediate sleevelike member separating said valves, said valves respectively controlling the flow of operating fluid to the opposite ends of said cylinder by controlling the communication of said passage means with said fluid supply, and valve-throwing means for subjecting said valves to valve-throwing pressures to move said valves into their different operating positions, said valves adapted abuttingly to engage said sleevelike member and being movable toward and from one another and when in their remote positions momentarily concurrently completely cutting off communication of both of said passage means with said fluid supply and each, through said sleevelike member, exerting in its full open position a force for holding the other valve closed.

6. A pressure fluid motor comprising, in combination, a cylinder, a piston therein, and fluid distribution means for the motor including passage means for supplying operating fluid to the opposite ends of said cylinder at the opposite sides of said piston respectively, an operating fluid supply, fluid distributing valve means including a pair of relatively movable valves and an intermediate sleevelike member separating said valves, said valves movable into abutting engagement with said sleevelike member and respectively controlling the flow of operating fluid to the opposite ends of said cylinder, for controlling the communication of said passage means with said fluid supply, and valve-throwing means for subjecting said valves to valve-throwing pressures to move said valve into their different operating positions, said valves upon relative movement toward one another abuttingly engageable with said sleevelike member and each of said valves upon relative movement from the other movable out of such abutting engagement and said valves when in their positions away from one another with one of them out of abutting relation with said sleevelike member momentarily concurrently completely cutting off communication of both of said passage means with said fluid supply.

7. In a pressure fluid motor, the combination comprising a cylinder having a bore, a piston reciprocable in said cylinder bore, and fluid distribution means for supplying pressure fluid to and exhausting fluid from said cylinder to effect reciprocation of said piston comprising means providing a valve chest, a pair of relatively movable annular fluid distributing valves and a cooperating intermediate sleevelike member separating said valves, said valves movable into and out of abutting relation with said sleevelike member, said valves and sleevelike member cooperating to divide said valve chest into inner and outer spaces and end pressure spaces at the remote ends of said valves, means for effecting movement of said valves relative to each other and said sleevelike member into their different normal operating positions in said valve chest, means for supplying motive pressure fluid to one of said inner and outer spaces, said valve-movement-effecting means including means for supplying pressure fluid to and exhausting fluid from others.

of said inner and outer pressure spaces for effecting movement of said valves into certain of their operating positions, and means providing fluid supply passages for connecting said end pressure spaces respectively with the opposite ends of said cylinder bore, said valves respectively controlling the flow of pressure fluid from the pressure fluid supply space through said end pressure spaces to said supply passages.

8. In a pressure fluid motor, the combination comprising a cylinder having a bore, a piston reciprocable in said cylinder bore, and fluid distribution means for supplying pressure fluid to and exhausting fluid from said cylinder bore to effect reciprocation of said piston comprising means providing a valve chest, a pair of relatively movable fluid distributing valves movably mounted in said valve chest and an intermediate annular member separating said valves, said valves and annular member arranged in coaxial relation and having open centers, and the pressure fluid flowing to one end of said cylinder bore through the open centers of said valves and annular member, means for effecting movement of said valves relative to one another and said annular member into their different normal operating positions in said valve chest, and means providing supply passages leading from the opposite ends of said valve chest respectively to the opposite ends of said cylinder bore, said valves respectively controlling the flow of pressure fluid through the ends of said valve chest to said supply passages.

9. In a pressure fluid motor, the combination comprising a cylinder, a piston reciprocable in said cylinder, and fluid distribution means for the motor including means providing a valve chest, a pair of relatively movable valves and an intermediate sleevelike member separating said valves and with which the latter are movable into abutting engagement, one valve being adapted to exert, through said sleevelike member, a pressure tending to hold the other valve closed, fluid distributing passages leading from said valve chest to the opposite ends of said cylinder, a pressure fluid supply, said valves controlling the flow of fluid from said supply to said passages, and means for effecting throwing of said valves and sleevelike member into their different operating positions.

10. In a pressure fluid motor, the combination comprising a cylinder, a piston reciprocable in said cylinder, and fluid distribution means for the motor including means providing a valve chest, a pair of relatively movable valves and an intermediate sleevelike member separating said valves and with which the latter are movable into abutting engagement, one valve being adapted to exert, through said sleevelike member, a pressure tending to hold the other valve closed, fluid distributing passages leading from said valve chest to the opposite ends of said cylinder, a pressure fluid supply, said valves controlling the flow of fluid from said supply to said passages, and means for effecting throwing of said valves and sleevelike member into their different operating positions, said sleevelike member having end pressure areas adapted when exposed to be subjected to pressure fluid to hold the valve with which it abuts in closed position.

11. In a pressure fluid motor, the combination comprising a cylinder, a piston reciprocable in said cylinder, and fluid distribution means for the motor including means providing a valve chest, a pair of relatively movable valves and an intermediate sleevelike member separating said

valves and with which the latter are movable into abutting engagement, said valves having sleevelike bodies arranged in telescopic relation with said sleevelike member, one valve being adapted to exert, through said sleevelike member, a pressure tending to hold the other valve closed, fluid distributing passages leading from said valve chest to the opposite ends of said cylinder, a pressure fluid supply, said valves controlling the flow of fluid from said supply to said passages, and means for effecting throwing of said valves and sleevelike member into their different operating positions.

12. A pressure fluid motor comprising, in combination, a cylinder, a piston reciprocable therein, and fluid distribution means for the motor comprising means providing a valve chest, a pair of relatively movable fluid distributing valves and an intermediate element separating said valves and with which the latter are adapted to abut, said valves and intermediate element being movably mounted in said valve chest, one valve in one position adapted to exert, through said intermediate element, a force tending to hold the other valve closed, fluid distributing passage means controlled by said valves for conducting motive fluid to the opposite ends of said cylinder, and valve-throwing means controlled by said piston for throwing said valves and intermediate element into their different operating positions.

13. A pressure fluid motor comprising, in combination, a cylinder, a piston reciprocable therein, and fluid distribution means for the motor comprising means providing a valve chest, a pair of relatively movable fluid distributing valves and an intermediate element separating said valves and with which the latter are adapted to abut, said valves and intermediate element being movably mounted in said valve chest and arranged in sliding telescopic relation, one valve in one position adapted to exert, through said intermediate element, a force tending to hold the other valve closed, fluid distributing passage means controlled by said valves for conducting motive fluid to the opposite ends of said cylinder, and valve-throwing means controlled by said piston for throwing said valves and intermediate element into their different operating positions.

14. A pressure fluid motor comprising, in combination, a cylinder, a piston reciprocable therein, and fluid distribution means for the motor comprising means providing a valve chest, a pair of relatively movable fluid distributing valves and an intermediate element separating said valves and with which the latter are adapted to abut, said valves and element being movably mounted in said valve chest, one valve in one position adapted to exert, through said intermediate element, a force tending to hold the other valve closed, fluid distributing passage means controlled by said valves for conducting motive fluid to the opposite ends of said cylinder, and valve-throwing means controlled by said piston for throwing said valves and intermediate element into their different operating positions, said intermediate element having pressure areas adapted, when exposed, to be subjected to pressure fluid to hold the valve with which it abuts in closed position.

15. A pressure fluid motor comprising, in combination, a cylinder, a piston reciprocable in said cylinder, and fluid distribution means for the motor comprising means forming a valve chest, passages respectively adapted to transmit operating medium from said valve chest to the oppo-

site ends of said cylinder and a pair of relatively movable valve elements and an intermediate element separating said valve elements, said several elements arranged in said valve chest, said fluid distribution means further including means for transmitting pressure variations in the cylinder to said valve chest to act on said several ele-

ments, said valve elements each when in full open position exerting on the other a holding pressure, and said intermediate element when said valve elements are both closed exerting on the latter in turn intermittent holding pressures.

JOHN C. CURTIS.

CHARLES F. OSGOOD.
